UNITED STATES PATENT OFFICE.

PHILIP S. SMITH, OF BROOKLYN, NEW YORK, ASSIGNOR OF THREE-FOURTHS TO HARRY B. SMITH, OF BROOKLYN, NEW YORK, J. STOGDELL STOKES, OF MOORESTOWN, NEW JERSEY, AND WINFIELD SCOTT SMITH, OF PAWTUCKET, RHODE ISLAND.

MACHINE FOR COVERING PAPER BOXES.

SPECIFICATION forming part of Letters Patent No. 690,377, dated December 31, 1901.

Application filed November 6, 1900. Serial No. 35,613. (No model.)

To all whom it may concern:

Be it known that I, PHILIP S. SMITH, a citizen of the United States, residing at Brooklyn, New York, have invented certain new and useful Improvements in Machines for Covering Paper Boxes, of which the following is a specification.

This invention relates to certain new and useful improvements in box-covering machines, and has for its object to simplify and improve the construction and operation generally of this type of machines and to increase the output and improve the character of work done to a marked degree as compared with machines heretofore contemplated for this purpose, but which latter have never, to my knowledge, been put into practical operation.

The machine forming the subject-matter of the present invention does not concern itself with the cutting or setting up of the box-blank, but is designed to apply a covering-blank of paper or other material to the box after the same has been set up and the corners stayed or fixed into position by any of the well-known means or methods now generally employed for accomplishing this end.

Briefly and generally stated, the invention comprises a suitable frame to support and carry the operative parts of the machine, a reciprocating plunger to support and carry the box to be covered, suitable covering devices between which the said plunger is arranged to travel, whereby the sides and ends of the covering-blank are affixed to the sides and ends, respectively, of the box and the end-flaps turned in, and a receiving-table for the box having a top plate normally located below the covering devices and in the path of movement of the plunger, which table may or may not be yielding, as desired.

The invention also comprises suitable means for stripping the box from the plunger as the latter reaches the table, so that the "covered" box will be delivered thereon.

It also comprises suitable means for simultaneously and quickly and accurately adjusting or setting the covering-rolls and turn-in devices to accommodate boxes of various sizes.

The invention also contemplates a simple and durable arrangement of means for imparting movement to the reciprocating plunger and turn-in devices.

The invention further consists in providing suitable guards or protectors for the covering devices or rolls to prevent the latter from becoming gummed during the movement of the plunger therebetween, thus preventing the covering material or blank from becoming soiled or gummed.

The invention also contemplates the employment of suitable auxiliary holding means for the blank during its passage between the covering devices when a blank is employed that has only its edges or margins gummed.

The invention further comprises suitable auxiliary strippers arranged between the covering devices and receiving-table, and finally the invention comprises other features of construction and arrangements of parts herein-after more fully described and then definitely pointed out in the claims which follow this specification.

In the accompanying drawings, in which similar reference characters designate corresponding parts, Figure 1 is a front elevation of a machine embodying the invention. Fig. 2 is an enlarged detail sectional view of the link connecting the plunger with the operating-lever. Fig. 3 is an elevation of the machine, taken from the right-hand side. Fig. 4 is a plan view of the same. Fig. 5 is an enlarged detail sectional view of the plunger and the covering devices with some of their attachments. Fig. 6 is a detail perspective view of the lower part of the plunger. Fig. 7 is a sectional view on the line 7-7 of Fig. 5. Fig. 8 is an enlarged sectional view on the line 8-8 of Fig. 5. Fig. 9 is a sectional view on the line 9-9 of Fig. 7. Fig. 10 is a detail perspective view showing the rod provided with a journal for carrying an end of one of the rolls and also the spring for pressing the rod outwardly. Fig. 11 is a similar view showing one of the brackets for carrying one of the upper rolls. Fig. 12 is a detail perspective view, partly in section, showing one of the devices for turning in the ends of the side flaps of the covering-blank. Fig. 13 is a detail perspective showing the bracket for supporting one of the lower rolls. Fig. 14 is a similar view showing the auxiliary covering-brush. Fig. 15 is an enlarged sectional view showing one of the covering-rolls with its guards cooperating with the form-block. Fig. 16 is a

similar view. Fig. 17 is an enlarged detail view showing the levers and links for conveying motion from the operative cam to the turning-in device. Fig. 18 shows the opened 5 face of the cam for operating the plunger. Fig. 19 is an enlarged detail sectional view showing one of the supports for the receiving-tables. Fig. 20 is a plan view of the clutch mechanism for conveying motion from the 10 pulley-shaft to the main driving-shaft of the machine. Fig. 21 is a side view of the same. Fig. 22 is an end view of the same. Fig. 23 is a detail view showing the members of the 15 clutch. Fig. 24 is a plan view of the covering-blank. Fig. 25 is a perspective view of the blank and the box-body. Figs. 26, 27, and 28 are perspective views of the box-body and covering-blank, showing the respective 20 results of the successive operations of the machine. Figs. 29 and 30 are detail sectional views showing the auxiliary holding devices or brushes in operative position, the two views 25 showing the plunger in different positions.

The framework supporting the several operative parts of the machine may be of any 30 construction suitable in the premises. In the present instance it consists, primarily, of the table A, the legs A', carrying the same, the standard A², mounted on said table at one side of the latter, and the base-plate A³, secured to the lower ends of the legs. In the central part of the table is an opening A⁴ in line with the path of travel of the boxes through the machine. Mounted on the 35 table are the devices for covering the boxes with the blanks, and carried by the standard is the mechanism for conveying the boxes through the machine and between the covering devices. The covering devices operate 40 successively to affix the side flaps of the blank to the sides of the box, to turn in the ends of the side flaps against the ends of the box, to affix the end flaps to the ends of the box, and 45 to press the blank firmly to the bottom of the box.

The devices for affixing the side flaps consist of the rolls B B, adjustably mounted on opposite sides of the table A and above the opening A⁴ therein. As both rolls and their 50 adjusting mechanism are alike, a description of one will suffice for both. In the top of the raised portion B' of the table and extending from the opening A⁴ is a guideway B², in which is placed the movable bar B³. The latter has a longitudinal slot B⁴, provided with countersunk sides. A bolt B⁵ passes through said slot with its head registering with the countersunk sides of the same and an opening in the raised portion B' of 55 the table. A thumb-nut B⁶ is turned onto the lower end of the bolt. When the thumb-nut is loosened, the bar B³ can be moved to or from the opening A⁴ in the table, and by 60 tightening the same it can be secured in any position to which it may be moved. On the inner end of the bar B³ is a yoke B⁷, with bifurcated ends B⁸. Passing through each bi-

furcated end is a rod B⁹, adapted to move back and forth therein. (See Figs. 10 and 11.) The forward movement of the rod is 70 limited by the pin B¹⁰. It is normally held in an advanced position by the spring B¹¹, placed around the same between the members of the bifurcation of the end of the yoke. Through the rod a second pin B¹² 75 passes, and when the rod is moved backward this pin engages with the spring, and the latter thereby resists such movement. In the forward ends of the rods B⁹ are bearings in which are journaled the ends of the shaft of 80 the roll B. By means of this mechanism the rolls can be adjusted relatively to the path of travel of the boxes through the machine to accommodate boxes of various widths, and through the action of the springs B¹¹ the 85 rolls will exert a yielding pressure on the covering-blank and also adapt themselves to any slight irregularity in the sides of the boxes.

It often happens that the covering-blank after it has been gummed warps or curls up 90 at its edges. When this happens, the gummed surface of the blank is apt to come in contact with the rolls and gum them, so that they in turn will gum and soil the faces of the succeeding boxes, and sometimes the 95 blank adheres to a roll and is torn thereby. This is prevented by a guard B¹³, (see Figs. 15 and 16,) carried by the yoke B⁷. On the ends of the latter are secured the spring-clips B¹⁴ for holding the guard in place. The 100 guard is formed of a strip of cardboard or other suitable material, and it projects over the roll in such a way that it first engages the gummed flap of the blank and turns it upwardly as the box descends, so that the 105 roll can only contact with the outer side of the blank, which is not gummed. When the guard becomes soiled, it can be readily replaced by a fresh one.

It is to be noted that after the side flap of 110 the blank is turned up it projects above the edge of the box, and the gummed inner surface of the projecting edge is apt to contact with the form-block, and thereby gum the latter. (See Fig. 15.) If the form-block 115 should become so gummed, on its return the rolls would become gummed or soiled also. To avoid this, a second guard B¹⁵ is secured to the under side of the yoke and projects beneath the roll. This guard is made of rubber or of a suitable material which can be 120 bent and when released will resume its original shape. It is of such a width that when the form-block returns without the box as to be engaged and bent around the roll between 125 the latter and the form-block. In this way any portion of the form-block that may be 130 gummed or soiled is prevented from contacting with the roll. For the sake of clearness the guards B¹³ and B¹⁵ are not shown as being applied to all the rolls in the main views of the machine; but it is to be understood that they can be so used.

In certain classes of work it may be prefer-

able to use brushes instead of the rolls B B and also those in the mechanism for affixing the end flaps, to be hereinafter described. Such a substitution can be readily accomplished, as the bearings for the shafts of the rolls are open.

Immediately below the rolls for affixing the side flaps of the blanks to the sides of the box and partly within the raised portion B' 10 of the table is located the mechanism for turning in the ends of the side flaps. As the parts of this mechanism on opposite sides of the path of travel through the machine are duplicates, a description of one will be sufficient. 15 Projecting from the under side of the slide-bar B⁸ are the lugs C, one back of the other. Through openings C' in the lugs the parallel rods C² pass and are adapted to be moved back and forth therein. The movement of 20 these rods back and forth is limited by the collars C³ and the tie-rod C⁴ engaging with the lugs. The tie-rod is adjustable on the rods, so that the forward movement can be regulated. Supported on the forward ends of the 25 parallel rods C² is the cross-piece C⁵, rectangular in cross-section. On each end of the cross-piece is a block C⁶, adjustable thereon and provided with a set-screw C' for holding it in its adjustment. Clamped between the 30 plate C⁸ and the face of the block is the wiper C⁹, formed of resilient metal. The forward end of the wiper is bent to form a convex rubbing-surface C¹⁰ for turning in the end of the side flaps without injuring the paper. 35 (See Fig. 12.) By means of the clamping-plate C⁸ and the screws C¹¹, passing through the same into the block C⁶, the wiper can be adjusted relatively to the block to accommodate boxes of different forms—those with inclined 40 sides, for example. By adjusting the blocks C⁶ on the cross-piece C⁵ the wiper can be regulated to accommodate boxes of different lengths. As the cross-piece is rectangular in 45 cross-section, as well as the openings in the blocks, the latter are prevented from turning on the former.

It is to be observed that the mechanism on each side of the machine for turning in the ends of the side flaps is carried by the slide-bar B⁸ on its respective side. The collars C³ are so located on the rods C² that when the said rods are in a retracted position and the said collars are in contact with the forward lug C the forward edges of the wipers C⁹ will 50 extend to the path of travel of the boxes through the machine, but no farther. The forward movement of the wipers is limited by the tie-rod C⁴ on the rods C² engaging with the rear lug C, projecting from the under side 55 of the slide-bar B⁸.

In making a loosely-wrapped box—that is, one in which the covering-blank is only gummed at its edges—after the side flaps are turned up by the rolls B they will not retain 60 their positions after the box leaves the rolls, and consequently the blank is apt to become displaced, as none of the gummed surface of

the blank is pressed into contact with the box by the rolls. To retain the blank in place, 65 holders are provided for pressing the side flaps of the blank against the box during the action of the wipers for turning in the ends of the flaps. (See Fig. 14.) To the under side of the yoke B⁷ are adjustably secured the angle-irons B¹⁶, and to the latter are attached the brushes B¹⁷, which form the 70 holders. These brushes are directly beneath the rolls B and will engage with side flaps of the blank and hold them against the box until 75 the wipers turn in their ends. As that portion turned in by the wipers is gummed, it will adhere to the box and the blank thereby 80 will be held in place during the rest of the operation.

Mechanism is provided for reciprocating 85 the wipers so that they will be advanced after a box has passed the rolls B to turn in the ends of the side flaps. Pivoted to the hanger D, projecting from the under side of the table A, is the T-shaped lever D'. One of the arms 90 D² of the latter has at its free end a friction-roll D³, engaging with the groove D⁴ in the cam D⁵, mounted on the shaft S. Under opposite sides of the table A are journaled the shafts D⁶, and on the latter are secured the 95 crank-arms D⁷, which engage with the tie-rods C⁴. Other crank-arms D⁸ are respectively secured on the shafts D⁶, and their free ends are respectively connected with the opposite ends of the cross-arm D⁹ of the T-shaped lever by the links D¹⁰. When the cam 100 D⁵ is rotated, the groove D⁴ in the same by reason of its form engaging with the friction-roll D³ oscillates the T-shaped lever, and through the intervening mechanism the 105 wipers C⁹ are simultaneously thrust forward at regular intervals into the path of travel of the boxes through the machine. This movement of the wipers is so timed as to operate just after the box that is being covered leaves 110 the rolls B to turn in the ends of the side flaps. By mechanism hereinafter to be described while the wipers are acting the travel of the box through the machine is stayed.

After the turn-in devices have been moved 115 forward to affix the ends of the flaps to the ends of the box, as seen in Fig. 27, said devices are by reason of the formation of the groove D⁴ in the cam D⁵ held stationary, or, in other words, are caused to remain in contact 120 with the ends of the box until the form-block G, hereinafter described, has carried the box from between them. This operation is of considerable importance, for if the wipers or turn-in devices were moved back to the starting-point before the box was moved downward 125 toward the second set of covering-rollers there would be a tendency to pull the ends of the flaps away from the ends of the box after they had been once affixed thereto, owing to 130 the fact that the gum would not have had an opportunity to set or dry.

Means are provided for affixing the end flaps of the blank to the ends of the box. Im-

mediately below the mechanism for turning in the ends of the side flaps are two rolls E E on opposite sides of the path of travel of the box through the machine. As the rolls and their supports are alike a description of one will do for both. On the top of the table is a slide-bar E', mounted in the guideway E², leading to the central opening of the table, and it is provided with an elongated slot E³, having countersunk side E⁴. Passing through this elongated slot and a suitable opening in the table is the bolt E⁵, with its head registering with the countersunk sides. A thumb-nut E⁶ is turned onto the lower end of the bolt and by means of the same the slide-bar can be secured in its adjustment. The slide-bar carries at its forward end a cross-bar E⁶, the ends of which are bifurcated. Through openings E⁷ in each bifurcated end a rod E⁸ passes and has in its forward end a bearing E⁹. (See Fig. 13.) The rod is movable longitudinally and is normally pressed forward by the action of the spring E¹⁰, coiled around the same between the members of the bifurcation of the same. A pin E¹¹ passes through the rear end of the rod and limits its forward movement. A second pin E¹² passes through the forward end of the rod inside of the bifurcation and bears on one end of the spring, so that when the rod is moved to the rear the said pin will engage with the spring and the latter thereby will oppose such movement of the rod. In the bearings E⁹ in the forward ends of the rods E⁸ are journaled the ends of the shaft of the roll E.

The positions of the rolls E E are such that they are at right angles to the rolls B B and are adjustable relatively to the path of travel through the machine, so that when a box leaves the devices for turning in the ends of the side flaps it will be engaged by the said rolls to turn up the end flaps of the covering-blank. The adjustable slide-bars E' permit the rolls to be adjusted to boxes of different lengths, and the spring-pressed rods E⁸ permit them to adjust themselves to any slight variation in size and to any unevenness there may be in the box ends.

Mechanism is provided for carrying the box that is to be covered through the machine to present it successively to the several mechanisms for affixing the covering-blank. This consists, essentially, of a plunger provided with means for reciprocating it in the path of travel of the boxes through the machine, a form-block attached to the lower end of the plunger on which the box which has been previously set up and stayed is placed, clips for holding the box on the form-block, and means for stripping the box from the form-block after the completion of the operation.

The standard A² has a head consisting of two members A⁵ and A⁶, respectively. Attached to the outer end of the member A⁵ is a vertical guideway F, in which the plunger F' is adapted to move. The latter is reciprocated by the lever F², to which it is connected by the

adjustable link F³. (See Fig. 2.) The link is slotted lengthwise, and movable therein is the block F⁴, having a projecting wrist-pin engaging with the free end of the lever. Journaled in the upper end of the link is the rod F⁵, provided with a hand-wheel F⁶ for turning the same. The lower end of this rod is screw-threaded and engages with the block F⁴. By means of this connection between the lever and the plunger the latter can be adjusted to adapt the machine to boxes of different heights. A nut F⁷ is provided for clamping the block in place after the adjustment has been made. The lever is oscillated by the cam F⁸, mounted on the upper end of the shaft S. The cam consists of a metal cylinder on the periphery of which is a guideway or groove F⁹. With the latter engages the friction-roll F¹⁰, journaled on one side of the lever between the latter's fulcrum-point and the end to which the plunger is attached. The formation of the groove F⁹ is such that when the cam is rotated the lever will be oscillated, and thereby a reciprocating movement imparted to the plunger F'. A counterpoise F¹¹ is mounted on the end of the lever opposite to that connected with the plunger to counterbalance the weight of the latter.

A form-block G is attached to the lower end of the plunger. It is shaped to fit the inside of a box and forms a backing against which the sides are pressed during the operation of the covering-affixing devices. It is secured to the holder G', and the stem of the latter is inserted in the lower end of the plunger. The form-block is readily removable from the holder, and a number of the same of different dimensions are kept on hand to accommodate boxes of different dimensions. In the sides of the form-block are the recesses G², adapted to receive the auxiliary stripping-rods hereinafter to be described. (See Figs. 1, 5, and 6.)

Clips H are provided for holding the boxes on the form-block during the first part of the downward stroke of the plunger. They are adjustably mounted on the rods H', projecting from the opposite ends of the yoke H², which latter rests by gravity on the form-block. The yoke is secured to the lower extremities of the vertical rods H³, which rods move freely through the perforated lugs H⁴, projecting from opposite sides of the guideway F. The downward movement of the rods is limited by the collars H⁵, adjustably mounted thereon. When the plunger is in an elevated position, the yoke H² rests on the holder G' by gravity. The box that is to be covered is placed on the form-block, and its ends are forced between the ends of the form-block and the clips H, and is thereby prevented from falling off until it is engaged by the covering devices. As the plunger descends the clips and their supports are carried with it until the collars H⁵ contact with the upper lugs H⁴. By this time the box has become engaged by the rolls B for affixing the side flaps, and by

- their pressure the box is held in place on the form-block, and consequently the clips are not further needed for that purpose. As the plunger continues by reason of the collars H^5 5 contacting with the lugs H the clips are withdrawn from the box. On the return stroke of the plunger the block G engages with the yoke H^2 , and the clips are carried up with it in a position to receive another box. 10 The adjustable collars H^5 permit the movement of the clips to be regulated as the plunger is adjusted to accommodate boxes of different heights.

Stripping mechanism for removing the boxes from the form-blocks after they have been covered by the blank is provided. Rods J are located in the vertical grooves J' in the opposite sides of the plunger F' and are longitudinally movable therein. They pass 15 through bearings in the lower end of the plunger and the plate J^2 , secured to the top of the guideway F . To retard the movement of the rods relatively to the plunger, friction-pins J^3 , mounted in the plate J^2 , bear upon 20 the rods. The friction-pins are forced against the rods by the springs J^4 , and the pressure of the latter is regulated by the screws J^5 , turned into the plate J^2 and bearing on said 25 springs. The downward movement of the rods relatively to the plunger is limited by the tie-plate J^6 , adjustably secured to their upper ends, coming in contact with the upper end of the plunger. Their upward movement is limited by the tie-plate J^7 , adjustably 30 secured to their lower ends, coming in contact with the lower end of the plunger. The lower ends of the rods pass freely through the holder G' and the form-block G , which are perforated for the purpose. The movement 35 of the rods relatively to the plunger is so limited by the tie-plate J^7 that when the rods are at their highest limit in the plunger the lower extremities of the rods will be flush with the bottom of the block. By adjusting the tie-plate J^7 the rods can be regulated to operate 40 with blocks of different thicknesses. As the plunger moves downwardly its lower end will engage with the plate J^7 , and thereby carry the rods J with it. After it has completed its 45 downward stroke the plunger starts on its return stroke. The rods, whose lower ends rest on the bottom of the box, will be held by the friction-pins J^3 . As the upward movement of the plunger is continued the rods, remaining 50 stationary, will strip the box from the form-block, as they will not start to ascend until the upper end of the plunger engages with the tie-plate J^6 , attached to the upper ends of the rods. By adjusting the tie-plate 55 on the rods the engagement of the plunger with the stripping-rods to raise them against the action of the friction-pins can be regulated, so that boxes of different heights can be accommodated. When the plunger reaches 60 the highest limit of its return stroke, the lower ends of the stripping-rods will project below the form-block. Unless these projecting ends

are withdrawn the next box cannot be placed on the form-block. This is done by the plunger commencing its downward stroke and continuing the same until the rods are sheathed. When the rods are completely sheathed, the downward movement of the plunger is stopped automatically by a mechanism hereinafter to be described.

When the machine is operating to cover comparatively large boxes made of flimsy or thin material, the stripping-rods pressing upon the bottom of the box bulge out the same, and this has a tendency to cause the 80 sides of the box to bind upon the form-block. Sometimes this binding is so tight that the rods punch holes through the bottom of the box and spoil it. To avoid this, means are provided to aid the stripping-rods in removing the box from the form-block. (See Figs. 1, 5, 7, and 13.) To the under sides of the slide-bars E' , carrying the lower rolls for affixing the end flaps of the blank, are adjustably attached the auxiliary strippers K . Each 85 of the latter is formed of a piece of spring metal bent to form an obtuse angle and is provided with a slot K' , through which a screw K^2 passes into the slide-bar. By means of the slot and screw the stripper can be adjusted on the slide-bar. When properly adjusted, the free end of the stripper projects slightly into the path of travel of the box through the machine, so that it will register with the recess G^2 in the form-block. As the 90 plunger descends the box on the form-block will contact lightly with the auxiliary strippers, but not with pressure enough to injure the covering, as the strippers are elastic and are easily bent aside. After the box passes 95 the strippers resume their normal positions and their lower ends will be in positions to register with the recesses G^2 in the opposite side of the form-block on the upward movement of the plunger and engage with the upper 100 edges of the box, and thereby aid in the removal of the latter. As the auxiliary strippers are attached to the slide-bars E' they will be adjusted at the same time that the lower affixing-rolls are adjusted.

Beneath the main table A and at the lower limit of the path of travel of the box through the machine is located the receiving-table, having a flat top plate L . (See Figs. 1, 3, and 19.) Secured to the base-plate A^3 is the 110 standard L' , having at its upper end the four arms L^2 . In the outer end of each arm is a socket L^3 , through which the bolt L^4 passes. The upper end of the bolt is secured to a corner of the top plate L , and the lower end 115 passes through the base of the socket and projects beneath the same, where it is provided with locking-nuts L^5 . In the socket surrounding the bolt and interposed between the top plate and the base of the socket is the spiral 120 spring L^6 . The latter normally tends to hold that part of the table above it in an elevated position, and its tension can be regulated 125 by the locking-nuts L^5 on the bolt. The

object of the top plate L is to receive the boxes after they have been stripped from the form-block and also to aid in affixing the blank to the bottom of the box. As the plunger F' reaches the lower limit of its stroke the bottom of the box and the blank are compressed between the form-block and the top plate of the table and are thereby firmly united. Owing to the springs the table is 10 yieldable and will therefore adapt itself to any unevenness in the bottom of the box and blank.

The formation of the groove F⁹ in the cam F⁸ is such as to operate the plunger through 15 the intervening mechanism, so that the form-block carried by the same will properly present the box and blank to the covering device. (See Figs. 1, 3, and 18.) At the beginning of a downward stroke of the plunger the friction- 20 roll is in engagement with the horizontal part F⁹¹ of the cam-groove. The box, with the blank attached to its bottom, is placed on the form-block and the machine is started. As the cam rotates the friction-roll passes through 25 the horizontal part F⁹¹ of the groove and enters the inclined part F⁹². As the cam continues to rotate the friction-roll will travel the inclined part F⁹³ and the lever F² will be depressed, and consequently the plunger with 30 it. While the friction-roll F¹⁰ is traveling through the inclined part F⁹² the plunger is forcing the form-block G between the upper rolls B, and the latter affix the side flaps of the blank to the sides of the box. Then as 35 the cam continues to turn the friction-roll enters the horizontal part F⁹³ of the groove, and while it is traveling through the same the plunger remains stationary. During this interval the wipers C⁹ advance and turn in 40 the ends of the side flaps. The cam D⁵ on the lower part of the shaft S is so adjusted that while the friction-roll F¹⁰ is traveling through the horizontal part F⁹³ of the groove in the upper cam the friction-roll D⁸ will be 45 engaged by the depressed part D⁴¹ of the groove D⁴ in the said lower cam. As the lower cam is rotated and the friction-roll D⁸ is in engagement with the depressed part D⁴¹ of the groove in the lower cam through the 50 intervening mechanism the wipers will be advanced and retracted. On the further rotation of the cam F⁸ the friction-roll is engaged by the inclined portion F⁹¹ of the groove, the lever F² is further depressed, the box is forced 55 between the lower rolls E, the end flaps of the blank are affixed to the ends of the box, and finally the box is pressed against the yieldable receiving-table and the blank is firmly affixed to the bottom of the box. As 60 the rotation of the cam continues, the upwardly-inclined portion F⁹⁵ of the groove engages with the friction-roll and the lever is raised, carrying with it the plunger, and completes the return stroke. During the upward 65 movement of the plunger the box is stripped from the form-block and deposited upon the receiving-table. After traveling through the

inclined portion F⁹⁵ the friction-roll enters the downwardly-inclined portion F⁹⁶ of the groove and passes into the horizontal portion F⁹¹. At this point the machine is automatically stopped. While the friction-roll is in engagement with the short inclined portion F⁹⁶ the plunger is moved downward a short distance to sheath the lower ends of the 75 stripping-rods.

The machine is driven by the shaft M, journaled in the bracket M', secured to the base-plate A⁸. (See Figs. 1, 2, 20, 21, 22, and 23.) On one end of the shaft is journaled the sleeve M², adapted to carry a pulley. A clutch mechanism is provided for transmitting motion from the sleeve to the shaft. The sleeve has a head from which the pins M³ project into the annular groove M⁴ in the face of the 85 disk M⁵, splined on the shaft. The locking member M⁶, movable longitudinally on the shaft, has spurs which register with the holes M⁷ in the disk M⁵. A fork M⁸ engages with the locking member, and by moving the same 90 the spurs can be projected into the annular groove M⁴ in the disk or withdrawn from the same. When the spurs are projected into the annular groove, they will be engaged by the pins M³ and the disk M⁵ thereby rotated. 95 As the disk is splined on the shaft, motion will be imparted to the latter. On the shaft between the bearings of the bracket the sleeve M⁹ is secured, so as to be rotated with the shaft. This sleeve carries the worm M¹⁰, 100 which engages with the gear M¹¹ on the lower end of the shaft S. By means of this mechanism motion may be transmitted from the sleeve M² to the shaft S. Also by means of the clutch mechanism the machine can be 105 started or stopped, as it may be desired.

The clutch mechanism is operated either by hand, the foot, or automatically. To the bracket M' is pivoted the bell-crank M¹². The latter is connected at one end by the rod M¹³, movable longitudinally in bearings in the bracket, with the fork M⁸ engaging with the locking member. The rod is normally pressed forward by the spring M¹⁴ to project the spurs of the locking member into the annular groove in the disk M⁵ to engage with the pins M³. The free end of the bell-crank carries a sleeve M¹⁵, in which the bar M¹⁶ is movable longitudinally. One end of the bar projects over the gear M¹¹ in a position to be engaged by the cam-block M¹⁷, mounted on the said gear. As the latter rotates the cam-block engages with the end of the bar and moves the bell-crank against the action of the spring M¹⁴ to draw, through the intervening mechanism, the locking member of the clutch mechanism from the other member, and thereby the operation of the machine is stopped. 115 120 125

On the base-plate A⁸ of the machine, in a position accessible to the operator, is pivoted the treadle M¹⁸. The latter carries an arm M¹⁹, the upper end of which engages with the bar M¹⁶. When the treadle is depressed, the bar is disengaged from the cam-block M¹⁷ 130

and the bell-crank released, so that the locking member of the clutch can be forced by the spring M^{14} into engagement with the other member and the machine thereby started.

5 Sometimes it may be desirable to stop the machine before an operation is completed. This is done by the hand-lever M^{20} , connected by the link M^{21} with the bell-crank. By moving the lever in one direction the bell-crank 10 can be oscillated to separate the members of the clutch to stop the machine, or by moving it in the opposite direction the members are brought together again to start the machine.

The process which the box and cover undergo consists in affixing the blank X , which has been previously gummed, to the under side of the box Y , so that the corners of the latter will register with the meeting points of the side and end flaps of the blank, as at 15 X' . (See Figs. 24 to 28, inclusive.) The box is then placed on the form-block and the machine is put in motion. As the box is carried between the upper set of affixing-rolls the side flaps X^2 will be pressed against the sides 20 of the box and affixed thereto. Then the wipers operate to turn in the ends X^3 of the side flaps against the ends of the box, and finally the end flaps are turned up against the ends of the box and are affixed thereto. 25 After the box has been stripped from the form-block the edges of the flaps are turned over the edge of the box by hand and the covering thereby completed.

While the hereinbefore-described embodiment of the invention is the preferred one, yet it can be departed from to a considerable extent without departing from its spirit.

Having thus described my invention, what I claim as new is—

40 1. In a box-covering machine, the combination with a reciprocating plunger adapted to support and carry the box to be covered, of covering devices between which the plunger is caused to move whereby the covering 45 material is affixed to the sides and ends of the box, and a receiving-table having a top plate located below the covering devices and across the path of movement of the plunger, said plate being arranged to coöperate with 50 the plunger after the latter has left the covering devices whereby the covering material is pressed firmly to the bottom of the box.

2. In a box-covering machine, the combination with a reciprocating plunger adapted 55 to support and carry the box to be covered, of covering devices between which the plunger is caused to move whereby the covering material is affixed to the sides and ends of the box, and a receiving-table having a yielding 60 top plate located below the covering devices and across the path of movement of the plunger, said yielding top plate being arranged to coöperate with the plunger after the latter has passed between the covering 65 devices whereby the covering material is pressed firmly to the bottom of the box.

3. In a box-covering machine, the combi-

nation with a reciprocating plunger adapted to support and carry the box to be covered, of covering devices between which the plunger is caused to move whereby the covering 70 material is affixed to the sides and ends of the box, a receiving-table having a top plate located below the covering devices and across the path of movement of the plunger, said 75 top plate being arranged to coöperate with the plunger after the latter has passed between the covering devices whereby the covering material is pressed firmly to the bottom of the box, and means for stripping the box 80 from the plunger when the latter reaches the said table to deliver the same thereon.

4. In a box-covering machine, the combination with a reciprocating plunger adapted to support and carry the box to be covered, 85 of covering devices between which the plunger is caused to move whereby the covering material is affixed to the sides and ends of the box, a receiving-table having a top plate located below the covering devices and across 90 the path of movement of the plunger, said plate being arranged to coöperate with the plunger after the latter has passed between the covering devices whereby the covering material is pressed firmly to the bottom of the 95 box, and means for positively holding the box upon the said top plate of the table during the initial upward movement of the plunger whereby the box is stripped therefrom.

5. In a box-covering machine, the combination with a vertically-reciprocating plunger adapted to carry the box to be covered, of devices for applying the covering material to the box, including devices for turning in ends of flaps, means for reciprocating said 100 plunger, means for operating said turning-in devices, and a vertical shaft arranged parallel with the plunger and carrying separate power devices for operating said plunger-reciprocating means and the means for operating the 105 turning-in devices.

6. In a box-covering machine, the combination with a reciprocating plunger adapted to carry the box to be covered, of devices for applying the covering material to the box including devices for turning in end flaps, a cam for reciprocating the plunger, a separate cam for operating the turning-in devices in 115 timed relation to the movement of the plunger, a vertical shaft arranged parallel to the 120 plunger and upon which both of said cams are mounted, and means for rotating said shaft.

7. In a box-covering machine, the combination with a reciprocating plunger adapted to support and carry the box to be covered, 125 of devices for applying the covering material to the box including devices for turning in end flaps, a receiving-table having a top plate located below the covering devices and across the path of movement of the plunger, means 130 for reciprocating the plunger, means for operating the turning-in devices in timed relation to the movements of the plunger, and a single shaft for imparting motion to the plun-

ger-reciprocating means and the means for operating the turning-in devices.

8. In a box-covering machine, the combination with a reciprocating plunger adapted 5 to support and carry the box to be covered, of devices for applying the covering material to the box including devices for turning in end flaps, a receiving-table having a top plate located below the covering devices and across 10 the path of movement of the plunger, a cam for reciprocating the plunger, a separate cam for operating the turning-in devices in timed relation to the movement of the plunger, a single shaft upon which both of said cams 15 are mounted, and means for rotating said shaft.

9. In a machine for covering boxes, the combination with a base having a standard rising therefrom, said standard being provided at its upper end with oppositely-extending arms, of an oscillating lever pivoted to one of said arms, a reciprocating plunger mounted to move in guides in the other of said arms, said lever having a connection 25 with the plunger, a vertical shaft arranged parallel with the standard, a cam mounted on the upper end of said shaft and co-operating with the oscillating lever to actuate the same, means for rotating said shaft, and covering devices between which the plunger is caused to move back and forth.

10. In a machine for covering boxes, the combination with a base having a standard rising from one side thereof, said standard 35 being provided at its upper end with two oppositely-extending arms one of which constitutes a guideway, of an oscillatory lever pivoted to one of said arms, a reciprocating plunger mounted to move in the guideway in 40 the other arm, a link connection between said lever and plunger, a vertical shaft arranged parallel with the said standard, a cam on the upper end of said shaft, an antifriction-roller mounted intermediate the ends of said oscillatory lever and co-operating with said cam, means for rotating the shaft, and covering devices between which the plunger is caused to move.

11. In a machine for covering boxes, the 50 combination with an elevated table having an opening therethrough and a vertical standard rising from one side of the table, said standard terminating at its upper end in two oppositely-extending arms, one of which is provided with a guideway that is disposed directly above and in line with the opening in the table, a reciprocating plunger freely movable in said guideway and through the opening in the table, a form-block carried by 55 the plunger, an oscillatory lever pivoted to the other arm of the cross-head, a vertical shaft arranged parallel with the standard, a cam on the upper end of said shaft, arranged adjacent to and having a connection with the oscillatory lever to actuate the latter, means for rotating said shaft, and covering devices carried by the table and arranged on oppo-

site sides of the opening therein, substantially as described.

12. In a box-covering machine, the combination with a supporting-frame having a bed-plate provided with a central opening and elevated portions arranged in line with each other upon opposite sides of said opening, of slide-bars supported by said elevated portions 75 of the bed-plate, slide-bars supported upon said top plate upon opposite sides of the opening at right angles to the first-named slide-bars, and covering devices carried by said slide-bars, substantially as described. 8c

13. In a box-covering machine, a supporting-frame having a bed-plate provided with a central opening and elevated portions arranged in line with each other upon opposite sides of said opening, guideways formed in 85 said elevated portions of the bed-plate, slide-bars adjustably mounted in said guideways, similar guideways formed on the bed-plate upon opposite sides of the central opening and at right angles to the first-named guideways, slide-bars adjustably mounted in said guideways on the bed-plate, and covering devices carried by the inner ends of the said slide-bars, substantially as described. 90

14. In a box-covering machine, the combination with a reciprocating plunger adapted to support and carry the box to be covered, of covering devices between which the plunger is caused to move, suitable clips for temporarily holding a box on the plunger until it reaches the covering devices, and means for holding the clips against movement to allow the plunger to move away from the clips to release the box. 95

15. In a box-covering machine, the combination with a reciprocating plunger adapted to support and carry the box to be covered, of covering devices between which the plunger is caused to move, suitable clips for temporarily holding the box on the plunger, and means for holding the clips against movement when said plunger passes between the covering devices. 105

16. In a box-covering machine, the combination with a reciprocating plunger adapted 115 to carry and support the box to be covered, of covering devices between which the plunger is caused to move, suitable clips for temporarily holding the box on the plunger, a box-receiving table having a top plate located 120 below the covering devices, and means for separating the plunger and clips when said plunger moves toward the table and before it passes between the covering devices so that the box will be free to be delivered thereon. 125

17. In a box-covering machine, the combination with a reciprocating plunger adapted to support and carry the box to be covered, of covering devices between which the plunger is caused to move, suitable clips for temporarily holding the box on the plunger, a box-receiving table having a yielding top plate located below the covering devices, means for separating the plunger from the 130

clips on its downward movement, and means for stripping the box from the plunger when the latter moves upward from the table.

18. In a box-covering machine, the combination with a reciprocating plunger adapted to support and carry the box to be covered, of a pair of side rolls, and a pair of end rolls, for applying the covering material to the sides and ends of the box, means for reciprocating the plunger between the side and end rolls, and a receiving-table having a top plate located below said rolls and in the path of movement of the plunger.

19. In a box-covering machine, the combination with a reciprocating plunger adapted to support and carry the box to be covered, of a pair of yielding side rolls and a pair of yielding end rolls, for applying the covering material to the sides and ends of the box, means for reciprocating the plunger between the side and end rolls, and a receiving-table having a yieldable top plate located below said rolls and in the path of movement of the plunger.

20. In a box-covering machine, the combination with a reciprocating plunger adapted to support and carry the box to be covered, of a pair of side rolls and a pair of end rolls, for applying the covering material to the sides and ends of the box, devices for turning in end flaps located between the two pairs of rolls, means for reciprocating the plunger, means for operating the turning-in devices, and a receiving-table for the box having a top plate located below the said rolls and in the path of movement of the plunger.

21. In a box-covering machine, the combination with a reciprocating plunger adapted to support and carry the box to be covered, of a pair of side rolls and a pair of end rolls for applying the covering material to the sides and ends of the box, devices for turning in end flaps, an oscillatory lever having a connection at one end with the plunger for reciprocating the latter, means for operating the turn-in devices, and a vertical shaft carrying two cams for imparting movement respectively to the oscillatory lever and the means for operating the turn-in devices.

22. In a box-covering machine, the combination with a reciprocating plunger adapted to support and carry the box to be covered, of a pair of side rolls, and a pair of end rolls, for applying the covering material to the sides and ends of the box, devices for turning in end flaps, an oscillating lever for reciprocating the plunger, means for operating the turning-in devices, and a vertical shaft carrying two cams, one of which actuates the oscillating lever and the other for operating the turn-in devices.

23. In a box-covering machine, the combination with a reciprocating plunger adapted to support and carry the box to be covered, of covering devices coacting with said plunger to affix the covering material to the sides and ends of the box, an oscillating lever for operating said plunger, a main driving-shaft

having an operative connection with said lever, a worm-wheel on said shaft, a continuously-driven shaft, a worm thereon meshing 70 with said worm-wheel, a clutch on said continuously-driven shaft, and a cam operable from the main driving-shaft and coöperating with the said clutch to cause the movement of the plunger to cease after each complete 75 rotation of said shaft.

24. In a box-covering machine, the combination with a vertically-reciprocating plunger adapted to support and carry the box to be covered, of suitable covering devices between 80 which the plunger is caused to move, and a pair of stripper- rods for stripping the box from the plunger when the latter reaches the limit of its downward movement.

25. In a box-covering machine, the combination with a reciprocating plunger adapted to support and carry the box to be covered, of a pair of side rolls and a pair of end rolls for affixing the covering material to the sides and ends of the box, means for moving the 90 plunger between the said rolls, and guards or protectors covering the rolls, substantially as described.

26. In a box-covering machine, the combination with a reciprocating plunger adapted 95 to support and carry the box to be covered, of a pair of side rolls and a pair of end rolls for affixing the covering material to the sides and ends of the box, means for moving the plunger between the said rolls, and removable strips covering the first pair of rolls.

27. In a box-covering machine, the combination with a reciprocating plunger adapted to support and carry the box to be covered, of covering devices between which the plunger is caused to move whereby the covering material is affixed to the sides and ends of the box, and guards or protectors arranged over the covering devices, substantially as described.

28. In a box-covering machine, the combination with a support for the box to be covered, covering devices coacting with said support for affixing the covering material to the sides and ends of the box, means for imparting a relative movement between said support and covering devices, and guards or protectors arranged over said covering devices.

29. In a box-covering machine, the combination with a support for the box to be covered, covering devices coacting with said support for affixing the covering material to the sides and ends of the box, means for imparting a relative movement between said support and covering devices, means for turning 115 in end flaps, and means for holding the covering material against the sides of the box until the turning-in means have acted.

30. In a box-covering machine, the combination with a support for the box to be covered, of covering devices coacting with said support for affixing the covering material to the sides and ends of the box, means for turning 125 in end flaps, and yieldable means for holding

- ing the covering material against the sides of the box until the turning-in means have acted to affix the end flaps to the box.
31. In a box-covering machine, the combination with a support for the box to be covered, of covering devices coacting with said support for affixing the covering material to the sides and ends of the box, means for turning in end flaps, and brushes for holding the covering material against the sides of the box until the turning-in means have acted to affix the end flaps to the box.
32. In a box-covering machine, the combination with a support for the box to be covered, of covering devices coacting with said support for affixing the covering material to the sides and ends of the box, and flexible protecting-strips arranged below the covering devices and adapted to cover the face of the latter.
33. In a box-covering machine, the combination with a reciprocating plunger adapted to support and carry the box to be covered, of a pair of side rolls and a pair of end rolls for affixing the covering material to the sides and ends of the box, means for moving the plunger between the covering devices, and flexible protecting-strips arranged below the rolls and adapted to cover the face of the latter on the ascent of the plunger.
34. In a box-covering machine, the combination with a support for the box to be covered, of covering devices coacting with said support for affixing the covering material to the sides and ends of the box, and guards or protecting-strips arranged above and below said covering devices, the lower guards being arranged to cover the face of the covering devices, substantially as described.
35. In a box-covering machine, the combination with a support for the box to be covered, of a pair of side rolls and a pair of end rolls coacting with said support for affixing the covering material to the sides and ends of the box, and guards or protecting-strips located above and below said rolls, the lower guards being adapted to cover the face of the rolls on the ascent of the plunger.
36. In a box-covering machine, the combination with a reciprocating plunger adapted to support and carry the box to be covered, of covering devices coacting with said plunger to affix the covering material to the sides and ends of the box, stripper-rods carried by the plunger, and auxiliary strippers arranged below the covering devices.
37. In a box-covering machine, the combination with a reciprocating plunger adapted to support and carry the box to be covered, of a pair of side rolls and a pair of end rolls adapted to affix the covering material to the sides and ends of the box, stripper-rods carried by the plunger, and auxiliary strippers located below the covering devices.
38. In a box-covering machine, the combination with a reciprocating plunger adapted to support and carry the box to be covered, of a pair of side rolls and a pair of end rolls adapted to affix the covering material to the sides and ends of the box, a receiving-table for the box located below the said side and end rolls, stripper-rods carried by the plunger, and auxiliary strippers located intermediate the table and rolls.
39. In a box-covering machine, the combination with a reciprocating plunger adapted to support and carry the box, of covering devices coacting with said plunger to affix the covering material to the sides and ends of the box, a cam for operating said plunger, a shaft on which said cam is mounted, a worm-wheel on said shaft, a continuously-driven shaft, a worm thereon meshing with said worm-wheel, a clutch on said continuously-driven shaft, and a cam-block on the worm-wheel co-operating with said clutch and acting to cause the movement of the plunger to cease after each complete rotation of the cam.
40. In a box-covering machine, a reciprocating plunger, a form-block carried by said plunger, rods supported upon and movable with the form-block, and clips carried by said rods for engaging the sides of said form-block to hold a box thereon.
41. In a box-covering machine, a reciprocating plunger, a form-block carried by said plunger, rods supported by gravity upon and movable with said form-block, clips carried by said rods adapted to engage with opposite sides of said form-block to hold a box thereon, and means for limiting the downward movement of said rods to disengage the clips from the form-block.
42. In a box-covering machine, a reciprocating plunger, a form-block carried by said plunger, freely-supported rods movable with said plunger, a yoke carried by said rods and supported by gravity upon the form-block, and clips adjustable on said yoke for engaging with said form-block to hold a box thereon.
43. In a box-covering machine, a reciprocating plunger, a form-block carried by said plunger, rods movable with said plunger, a yoke carried by said rods, clips adjustable on said yoke for engaging with said form-block for holding a box thereon, and means for limiting the downward movement of said rods to disengage the clips from the form-block.
44. In a box-covering machine, a guideway, a plunger reciprocable in said guideway, a form-block carried by said plunger, rods freely movable on bearings in said guideway and movable with said plunger, a yoke carried by said rods and supported by gravity upon the form-block, clips adjustable on said yoke for engaging with said form-block to hold a box thereon, and collars on said rods for limiting the downward movement of the same to disengage the clips from the form-block.
45. In a box-covering machine, a reciprocating plunger, a form-block carried by said plunger, rods movable with said plunger and supported by gravity upon the form-block,

- adjustable clips carried by said rods for engaging the sides of said form-block to hold a box thereon, and means for limiting the downward movement of said rods for withdrawing said clips from the form-block. 5
46. In a box-covering machine, a reciprocating plunger, a form-block carried by said plunger, stripping-rods movable in said plunger and passing through said form-block, and friction devices for retarding the movement of said rods relatively to the movement of said plunger. 10
47. In a box-covering machine, a reciprocating plunger, a form-block carried by said plunger, stripping rods carried by said plunger and movable therein and passing through said form-block, means for limiting the movement of said rods relatively to said plunger, and friction devices for retarding the movement of said rods relatively to the movement of said plunger. 15
48. In a box-covering machine, a guideway, a plunger reciprocable therein, a form-block carried by said plunger, stripping-rods carried by said plunger, and movable therein and passing through said form-block, and friction devices mounted on said guideway and engaging with said rods for retarding the movement of the same relatively to the movement of the plunger. 20
49. In a box-covering machine, a guideway, a plunger reciprocable therein, a form-block carried by said plunger, stripping-rods carried by said plunger and movable therein and passing through said form-block, and spring-pressed friction-pins mounted on said guideway and bearing on said rods for retarding the movement of the same relatively to the movement of the plunger. 25
50. In a box-covering machine, a guideway, a plunger reciprocable therein, a form-block carried by said plunger, stripping-rods carried by said plunger and movable therein and passing through said form-block, friction-pins mounted on said guideway and bearing on said rods for retarding the movement of the same relatively to the movement of said plunger, springs pressing said pins, and means for regulating the tension of said springs. 30
51. In a box-covering machine, a roll for pressing the flap of a blank to a box, an auxiliary holding device mounted beneath said roll for holding the flap in place that has been pressed by the roll, and means for turning in the ends of the flap held in place by the auxiliary holder. 35
52. In a box-covering machine, an adjustable roll for pressing the flap of a blank to a box, an auxiliary holding device mounted beneath said roll and adjustable with the same for holding in place the flap that has been pressed by the roll, and means for turning in the ends of the flap held in place by the auxiliary holder. 40
53. In a box-covering machine, an adjustable slide-bar, a roll carried by said slide-bar for pressing the flap of a blank against a box, an auxiliary holding device adjustably mounted on said slide-bar beneath said roll, and means for turning the ends of the flaps held in place by the auxiliary holder. 45
54. In a box-covering machine, an adjustable slide-bar, a roll carried by said slide-bar, angle-bars adjustably attached to said slide-bar, and a brush carried by said bars beneath said roll. 50
55. In a box-covering machine, a reciprocable plunger, a form-block carried by said plunger, covering devices between which the form-block moves, slide-bars adjustable relatively to the line of travel of said form-block, and strippers carried by said slide-bars for removing boxes from said form-block, said strippers being arranged below the covering devices and having their ends terminating in the path of movement of the form-block. 55
56. In a box-covering machine, a reciprocable plunger, a form-block carried by said plunger, stripping-rods carried by said plunger for removing boxes from said form-block, and auxiliary strippers adjustable to the line of travel of the form-block for aiding in the removal of boxes from the form-block. 60
57. In a box-covering machine, a reciprocable plunger, a form-block carried by said plunger, stripping-rods carried by said plunger for removing boxes from said form-block, slide-bars adjustable relatively to the line of travel of the form-block, and auxiliary strippers adjustably mounted on said slide-bars to aid in the removal of the box. 65
58. In a box-covering machine, a reciprocable plunger, a form-block carried by said plunger, slide-bars adjustable relatively to the line of travel of said form-block, rods movably mounted in said slide-bars, cross-bars carried by said rods, wipers adjustable on said cross-bars, and means for reciprocating said rods to move said wipers to and from the line of travel of said form-block. 70
59. In a box-covering machine, a reciprocable plunger, a form-block carried by said plunger, slide-bars adjustable relatively to the line of travel of said form-block, rolls carried by said slide-bars for affixing the flaps of a blank to a box wipers slidably mounted on said slide-bars for turning in the ends of the flaps affixed by said rolls and means for reciprocating said wipers to and from the line of travel of the form-block. 75
60. In a box-covering machine, the combination with a reciprocating plunger, of covering devices between which said plunger is caused to move, including devices for turning in ends of flaps, rods carrying said turning-in devices, rock-shafts for reciprocating said rods, a T-lever for operating said rock-shafts, and means for operating the T-lever. 80
61. In a box-covering machine, the combination with a reciprocating plunger adapted to support and carry the box to be covered, of a pair of side rolls and a pair of end rolls for affixing the covering material to the sides and ends of the box, devices for turning in 85

- ends of flaps located between said pairs of rolls, rods carrying said turning-in devices, rock-shafts for reciprocating said rods, a T-lever for operating said rock-shafts, and a cam for operating said T-lever.
62. In a box-covering machine, the combination with a reciprocating plunger adapted to support and carry the box to be covered, of a pair of side rolls and a pair of end rolls for affixing the covering material to the sides and ends of the box, wiping devices for turning in ends of flaps located between said pairs of rolls, rods carrying said wiping devices, rock-shafts for reciprocating said rods, cranks on said rock-shafts, a pivoted T-lever having link connections with said cranks, and a cam for operating said T-lever to cause the wiping devices to act when the plunger reaches a point between the said pairs of rolls.
63. In a box-covering machine, the combination with a reciprocating plunger adapted to support and carry the box to be covered, of a pair of side rolls and a pair of end rolls for affixing the covering material to the sides and ends of the box, laterally-adjustable wiping devices for turning in ends of flaps located between said pairs of rolls, a bar on which said wiping devices are mounted, rods carried by said bar, rock-shafts for reciprocating said rods, a T-lever for operating said rock-shafts, and a rotary cam for operating said T-lever, substantially as described.
64. In a box-covering machine, the combination with a reciprocating plunger, of covering-rolls between which said plunger is caused to move, wipers for turning in ends of flaps, rods carrying said wipers, means for reciprocating said rods to cause the wipers to move to and from the path of movement of the plunger, and means for limiting the movement of said rods and wipers.
65. In a box-covering machine, the combination with means for supporting and carrying the box to be covered, of slide-bars adjustable relatively to the line of travel of said box-supporting means, wiping devices for turning in the ends of flaps, slidably mounted on said slide-bars, and means for positively moving said wiping devices back and forth on the slide-bars, to and from the line of travel of the box-supporting means.
66. In a box-covering machine, the combination with means for supporting and carrying the box to be covered, of devices for turning in the end flaps of the covering-blank, comprising slidably-mounted wipers, and means for reciprocating the wipers to and from the line of travel of the box supporting and carrying means.
67. In a box-covering machine, the combination with means for supporting and carrying the box to be covered, of slidably-supported cross-bars arranged on opposite sides of the line of travel of the box-supporting means, wipers adjustable laterally on said cross-bars, and means for sliding said cross-bars to and from the line of travel of the box-supporting means.
68. In a box-covering machine, the combination with a reciprocating plunger adapted to support and carry the box to be covered, of covering devices between which the plunger is caused to move whereby the covering material is affixed to the sides and ends of the box, and a presser-plate arranged to operate with the plunger after the latter has passed between the covering devices and acting to press the covering material to the bottom of the box.
69. In a box-covering machine, the combination with means for supporting and carrying the box to be covered, of covering devices for affixing the covering material to the sides of the box, means for causing the box-carrying means to move the box between the said covering devices, and for stopping the movement thereof after the covering material has been affixed to two sides of the box, devices for turning the ends of the side flaps onto the ends of the box, means for moving the box away from said end-turn-in devices while the latter are in engagement with the sides of the box, and means for affixing the covering material to the ends of the box.
70. In a box-covering machine, the combination with a suitable bed-frame having a standard rising therefrom, and a cross-head supported by the standard, of a reciprocating plunger mounted to move in said cross-head, an oscillating lever having a connection with the plunger, covering-rollers between which the plunger is caused to move, end-turn-in devices for turning the ends of the side flaps of the covering-blank against the ends of the box, means for moving the box from between the said turn-in devices while the latter are in engagement with the ends of the box, and means for stripping the box from the plunger before it repasses the covering-rollers on the return stroke.
71. In a box-covering machine, the combination with means for supporting the box to be covered, of covering-rollers for pressing the covering material to the sides and ends of the box, end-turn-in devices for turning the ends of the side flaps of the covering material against the ends of the box, means for moving the box from between said end-turn-in devices while the latter are in engagement with the ends of the box, and means for stripping the box from the plunger before it repasses the rollers on the return stroke.
72. In a box-covering machine, the combination with means for supporting and carrying the box to be covered, of covering-rollers for pressing the covering material to the sides and ends of the box, end-turn-in devices for turning the ends of the side flaps of the covering material against the ends of the box, and means for moving the box supporting and carrying means away from said turn-in devices while the latter are in engagement with the box.

73. In a box-covering machine, the combination with means for supporting and carrying the box to be covered, of covering devices for affixing the covering material to the sides and ends of the box, end-turn-in devices for turning in the ends of the side flaps of the covering material against the ends of the box, means for moving said end-turn-in devices in engagement with the ends of the box 5 while the latter is held stationary to turn in the ends of the flaps, and means for moving the box from between said end-turn-in devices while the latter are in engagement with the ends of the box.
74. In a box-covering machine, the combination with a suitable bed-frame having a standard rising therefrom carrying a cross-head, of a reciprocating plunger mounted to move in guides in one arm of the cross-head, a form-block carried by the plunger, an oscillating lever pivoted to the other arm of the cross-head and having an adjustable connection with the plunger, covering-rollers between which the plunger is caused to move, means for oscillating the lever to move the plunger up and down between the covering devices, and means for stripping the box from the form-block after it has carried the box through the covering devices 10
